BATHTUB

Albert E. Thompson, Long Beach, Calif., assignor
of seven per cent to Zula Mae Crain Dunham

Application July 31, 1941, Serial No. 404,922

4 Claims. (Cl. 4—173)

This invention relates to an improved construction of bathtub, and more particularly to a bathtub particularly intended and adapted for use for taking foot baths while in a seated position, and which is especially advantageous for use by elderly persons, expectant mothers and convalescents.

More particularly, it is an aim of the invention to provide a novel construction of tub having a bottom provided with raised end portions forming seats which are adapted to be used for supporting the bather at different elevations relatively to the bottom of the tub and in a sitting position, and which are also well adapted for use in conjunction with one another for the bathing of infants and small children, in which case the infant or child can be placed upon one of said seat portions and the mother can sit upon the other seat portion while conveniently and safely bathing the child or infant.

Still a further aim of the invention is to provide a bathtub adapted to conserve upon the amount of water used in the taking of a bath.

Still another aim of the invention is to provide selectively operated heating means for heating said seat portions, and which heating means will also function to maintain the temperature of the water in the tub while taking a warm or hot bath.

Still a further aim of the invention is to provide a tub adapted to be used in conjunction with a conventional shower unit, and by means of which a shower may be taken while in a seated position.

Still a further aim of the invention is to provide a recess in a portion of the upper part of the outer side of the tub and which is so arranged relatively to one of the raised ends of the tub bottom that the user can readily get into or out of the tub without danger of slipping and without having to stand in the tub.

Other objects and advantages of the invention will hereinafter become more fully apparent from the following description of the drawing, which illustrates preferred embodiments of the invention, and wherein:

Figure 1 is a perspective view of one form of the improved bathtub,

Figure 2 is an enlarged longitudinal vertical sectional view of the same,

Figure 3 is a cross sectional view of the same taken substantially along a plane indicated by the line 3—3 of Figure 2, and

Figure 4 is a fragmentary perspective view of a modified form of the bathtub.

Referring more particularly to the drawing, wherein like reference characters designate like or corresponding parts throughout the different views, 10 designates generally one form of the bathtub constructed in accordance with the invention as illustrated in Figures 1 to 3. The bathtub 10 may be of conventional exterior shape and design and including a front wall 11, back wall 12 and end walls 13 and 14. The bathtub 10 may be of the built in type or in any case is adapted to be disposed with its rear wall 12 disposed against a perpendicular wall, indicated at 15, and to which is suitably secured in any manner a panel 16, as seen in Figure 1. The panel 16 is disposed above and adjacent the upper edge of the rear wall 12 and is provided with an elongated hand rail 17 which is adapted to be grasped by the user of the tub while getting into or out of the tub 10.

20 The tub 10 is provided with a novel construction of bottom, designated generally 18, and which is adapted to rest upon a suitable supporting surface 19. The bottom 18 is provided with raised end portions, designated generally 20 and 21. The raised portion 20 includes an upper, substantially horizontal seat portion 22 which is disposed below the level of the upper edges of the sides and ends of the tub, and a perpendicular front wall portion 23 which extends from the inner end of the seat portion 22 downwardly and which is disposed substantially parallel to the end walls 13 and 14. The lower portion of the end wall 13 combines with the seat portion 22 and the wall portion 23 to form a chamber 24, the bottom of which is closed by the surface 19 on which the tub 10 rests. End wall 13 is provided with an opening 25 which communicates with the chamber 24 and which is adapted to be normally closed by a removable door or panel 26.

30 The raised portion 21 includes an elongated seat portion 27 which extends from the end wall 14 to a point substantially intermediate of the ends of the tub 10 and which terminates in a downwardly extending perpendicular wall 28 which is disposed substantially parallel to the wall 23 and spaced therefrom. The seat portion 27 is disposed substantially below the level of the seat portion 22 and said seat portion 22 is adapted to be disposed at a height substantially equal to the height of a conventional chair seat. The seat portion 27, wall portion 28 and a part of the end wall 14 combine to form a chamber 29, the open bottom of which is closed by a portion of the supporting surface 19. The wall 14

is also provided with an opening 30 which communicates with the chamber 29 and which is adapted to be closed by a panel or closure 31. As best seen in Figure 2, the seat portion 27 is substantially longer, longitudinally of the tub 10, than the seat portion 22, and said seat portions are preferably corrugated or ribbed longitudinally on their upper sides as seen at 32.

Between the wall portions 23 and 29 is a bottom portion 33 which rests upon the surface 19 and which is disposed substantially below the levels of either the seat portion 22 or 27, and which combines with the wall portions 23 and 28 to form a channel or trough portion 34. The bottom portion 33 is provided with a drain outlet 35. Water supply pipes 36 extend upwardly through the surface 19 and into the chamber 24 and are provided with bib or faucet portions 37 which extend into openings 38 in the wall portion 23. The pipes 36 are adapted to be connected in a conventional manner to a water main or other suitable source of water supply and the bibs 37 are arranged to discharge into the channel or trough 34 below the level of the seat 27 so that the trough can be filled with water without wetting the seats.

The chambers 24 and 29 each contains a conventional electric heating unit of any suitable construction which units are designated 39 and 40, respectively.

The panel 16 contains three operating knobs 41, two of which control the two supply pipes 36 in a conventional manner, and the other of which is adapted to control a valve, not shown, of the drain opening 35 in a conventional manner. The panel 16 also contains two smaller switch operating knobs 42 which are adapted to be of any suitable conventional construction and connected in any suitable manner with the circuit of the heating elements 39 and 40 for selectively controlling said heating elements.

From the foregoing it will be obvious that a user could conveniently sit on the seat 22 while bathing the feet in the trough 34 or while resting the feet on the seat portion 27 for applying medicine to or otherwise treating the feet. Likewise, while sitting on the seat 27 a sponge bath can be taken with water from the trough 34 or the tub 10 could be filled sufficiently to submerge the seat 27 for bathing in an ordinary way. Also, a mother could conveniently sit on the seat 22 and bathe an infant on the seat 27. The tub 10 is obviously adapted to be disposed beneath a conventional shower unit, in a conventional manner, and either of the seat portions 22 or 27 may be used in conjunction with the shower unit to permit a shower to be taken while sitting in an upright position. In any of the

aforementioned or the many other uses to which the tub 10 adapts itself, the heating units 39 and 40 can be energized for heating the seats 22 and 27 so that the bather will be comfortably warm while bathing and the heat from the heating units will of course act to maintain the temperature of the water in the tub and to warm the water.

In the modified form of the tub, designated 10', and which is illustrated in Figure 4, the front wall 11' thereof is recessed in its upper edge as seen at 43, contiguous with the seat 27. The recessed portion 43 is provided with a longitudinal rim portion 44 which is disposed somewhat above the level of the seat 27. All other parts of the tub 10' correspond to the tub 10 and will therefore not be described.

It will be readily apparent that a convalescent or expectant mother could readily get into or out of the tub 10' without placing the weight of the body on the feet, while in the tub. This could be accomplished by sitting on the seat 27, from a standing position outside of the tub 10', and then swinging the legs over the rim portion 44 and into the tub. By reversing this procedure it will be readily apparent that the bather can get out of the tub without standing on any part thereof thus eliminating any danger of slipping while getting into or out of the bathtub.

30 Various modifications and changes are contemplated and may obviously be resorted to, provided they fall within the spirit and scope of the invention as hereinafter defined by the appended claims, as only preferred constructions of the bathtub have been disclosed.

I claim as my invention:

1. A bath tub having a bottom provided with raised end portions, said raised end portions forming seats of different elevations, within the depression of the tub, and the intermediate portion of the tub bottom combining with said seat portions to form a trough or channel portion, disposed transversely of the tub.

15 2. A tub as in claim 1, comprising a faucet associated with the tub and arranged to discharge into said trough or channel portion.

3. A tub as in claim 1, said seat portions forming chambers in the tub, and heating elements disposed in said chambers and adapted to be energized for heating said seat portions.

4. A tub as in claim 1, the lower of said seat portions being substantially longer than the other seat portion, and said tub being provided with a cutout portion in the upper part of one side wall thereof and which is disposed above and contiguous with said lower seat portion.

ALBERT E. THOMPSON.
